UNITED STATES PATENT OFFICE.

ALFRED HENRY WILLMANN, OF WIMBLEDON, ENGLAND.

SAFETY-SHUTTER FOR CINEMATOGRAPH-PROJECTORS.

1,361,430.

Specification of Letters Patent.

Patented Dec. 7, 1920.

Application filed August 25, 1919. Serial No. 319,570.

To all whom it may concern:

Be it known that I, ALFRED HENRY WILLMANN, a subject of the King of Great Britain, residing at 13 Mina Road, Merton Park, Wimbledon, Surrey, England, have invented new and useful Improvements in Safety-Shutters for Cinematograph-Projectors, of which the following is a specification.

10 My invention relates to safety shutters for affording protection against fire in cinematograph projectors, and to that class of such shutter having combined with it means whereby it is retained in the open 15 position so long as the film is intact but closes if the film breaks.

In apparatus of this class as heretofore constructed the releasing device for the safety shutter is placed in such a position 20 with relation to the gate or trap through which the film passes that it is necessary to draw the film out of the trap before the device operates. To overcome this objection it has been proposed to provide a duplicate 25 shutter to operate in case the film breaks before it enters the gate.

According to my invention I arrange the releasing device to bear against the film close to the point at which it issues from the gate so that the safety shutter will 30 operate almost instantaneously in case the film breaks in the gate.

In carrying out my invention I employ a pendulous arm or lever which presses upon 35 the film as it issues from the said gate and I combine with this lever a second lever carrying a catch which engages with the shutter to retain it open so long as the film is intact, but which should the film break and 40 allow the pendulous lever to move relatively thereto will release the said catch and allow the shutter to close.

My invention will be readily understood 45 by reference to the accompanying drawing, in which:—

Figure 1 is an elevation illustrating an arrangement wherein a single shutter is employed, and

Figs. 2 and 3 are sections on the lines 50 2—2, and 3—3, respectively of Fig. 1.

Fig. 4 is an elevation illustrating a modification of my invention, and

Fig. 5 is a section on the line 5—5, Fig. 4.

Fig. 6 is a plan of the same.

In the arrangement of my invention

shown in Figs. 1 to 3 *a* indicates the front plate and *b* the gate which is combined therewith and which, as shown, is designed to slide backward upon the rods *b*¹, *b*² to 60 allow the film *c* to be inserted between the said gate and said front plate. *c*¹, *c*² are the apertures formed in the front plate and gate respectively, through which the light is projected. *d* is the safety shutter which, as shown, is mounted on a pivot *d*¹ and which is cut away or shaped as at *e* to expose the aperture *c*¹.

In connection with this shutter *d* I provide a catch lever *f* which by engaging with a tooth *f*¹ on the said shutter will hold the latter to uncover the aperture *c*¹ as shown in the drawing, and in combination with the said catch lever I provide a pendulous arm *g* pivoted upon the plate *a* and the free in-turned end *g*¹ of which is designed to bear 75 against the film *c*.

In practice the catch lever *f* is formed with two arms, one of which carries a spring pawl *h* which constitutes the catch proper and engages with the tooth *f*¹ and the other of which at the end *h*¹ co-operates with an incline or curved surface *i* on the pendulous arm in such a manner that a spring *i*¹ which pulls upon the said lever *f* serves to press 85 the end *g*¹ of the pendulous arm against the film *c*, as clearly shown in Fig. 2.

k is an electric switch fixed upon the front plate *a* and which, as shown, is provided with four terminals, two of which are in the circuit of the operating motor and the other two in a bell or other alarm circuit. The contact bar or lever *l* of this switch is designed to be actuated by the shutter *d* when the latter is moved; as shown, the said shutter is provided with two arms *m*, *m*¹, the arm *m* serving, when the shutter is moved to uncover the aperture *c*¹, to strike the contact bar *l* and switch on the motor current, while the other arm *m*¹ is designed, in the case of a film breaking and releasing the shutter, to strike the contact bar and switch off the current from the motor and close the bell circuit to give an alarm.

It is to be understood that the construction of the switch and the manner in which it is combined with the shutter itself forms no part of my invention.

In the arrangement just described the film is maintained taut by a sprocket wheel *c*³ arranged below the pendulous lever and in case the film breaks, the lever will at once

swing inward under the action of the spring z^2 acting on the lever f and release the shutter which will close the aperture c^1 .

In practice I find it advantageous to provide for adjusting the pawl h with relation to the tooth f^1 according to the thickness of film employed, that is to say, I arrange that it does not gear so deeply for thick films as for thin films owing to the former not yielding so easily when broken. For this purpose I arrange the pivot of the lever f so that it can be moved longitudinally, this being advantageously effected by a screw f^2 , as shown clearly in Fig. 3.

15 In cases where the sprocket wheel which causes the travel of the film is arranged so close to the aperture c^1 that sufficient space is not afforded for applying the pendulous lever g between the aperture and the said 20 sprocket wheel, I advantageously make use of the arrangement illustrated in Figs. 4 to 6.

In this modification n is the pendulous arm which is arranged below the sprocket 25 wheel n^1 at which point the tension on the film is not sufficient to retain the pendulous arm in the required position to lock the shutter open. I therefore provide in conjunction with the said pendulous arm a pair of 30 rollers o, o^1 or other support, over which the film will run and between which the free end of the pendulous arm will pass, in such a manner, that so long as the film is intact the pendulous arm will remain in the position 35 shown in Fig. 5, but so that when the broken end of the film comes opposite to the gap between the said rollers the pendulous arm will swing to release the shutter.

In this modification of my invention the 40 gate which is to be opened for introducing the film is arranged on the opposite side of the plate a to that shown in Figs. 1 to 3 and the shutter is applied to the gate instead of to the front plate; also, the shutter instead 45 of being made in one piece is made in two sections p, p which allow of the shutter being made smaller than in the arrangement shown in Fig. 1. In this case the two sections are geared together as at q in Fig. 4, 50 and the catch lever r engages with only one of the said sections as shown in Fig. 4. This catch lever r operates in conjunction with the lever n in the same way as described with reference to Fig. 1.

55 The switch which controls the operating motor and is shown in Figs. 4 and 6, has its controlling arm s connected on one side of its pivot with one section of the shutter, say, by a chain t or other flexible connection, in such a manner that the opening of the shutter will serve to operate the switch to start the motor. The other end of the said operating lever is connected by a chain or the like to a trip lever u which will be

struck by one leaf of the shutter, when the latter drops, to open the switch to stop the motor.

In the switch shown in the drawing the contact arm v is pressed toward the operating arm by a spring w and a notch x is formed therein. When the shutter is open the arm s holds down the contact arm v as shown in Fig. 6. When, however, the shutter is released and the trip lever u is operated as above described the arm s is moved to the position indicated by the dotted lines in Fig. 4 in which it is opposite to the notch x , the said contact arm being thereby free to rise under the action of the spring w to open the switch to stop the motor. 80

Claims.

1. A cinematograph projecting apparatus including a film guide having an aperture for the projection of the light and a film driving or supporting roller adjacent to the 85 said guide, a pivotally mounted shutter movable in a plane parallel to that of the guide passage and designed to close said aperture, a rocking lever having one of its ends engaging the shutter for holding the 90 same in open position, a pendulous lever bearing upon one face of the film and engaging the other end of the rocking lever for holding the latter in locking position, and means operating upon breaking of the film to cause 95 the rocking lever to release the shutter to permit the same to close.

2. An apparatus of the kind defined in claim 1, in which the supports between which the film passes, are arranged adjacent the point at which the film passes from the driving or supporting roller, the part of the pendulous lever which engages the film being movable between the supports when the film breaks. 100

105 3. A cinematograph projecting apparatus including a plate and a film guide having registering apertures, a pivotally mounted shutter movable in a plane parallel to the face of said plate and designed to close said 110 apertures, a rocking lever having one of its ends engaging the shutter for holding the same in open position, a pendulous lever bearing upon one face of the film and engaging the other end of the rocking lever for holding the latter in locking position, and means operating upon breaking of the film to cause the rocking lever to release the shutter to permit the same to close. 115

4. An apparatus of the kind defined in 120 claim 5, in which rollers between which the film passes, are arranged adjacent the point at which the film issues from the film guide, and the part of the pendulous lever which engages the film being movable between the 125 rollers when the film breaks.
